UNITED STATES PATENT OFFICE.

CORNELIS BOL, OF EINDHOVEN, NETHERLANDS, ASSIGNOR TO N. V. PHILIP'S GLOEI-LAMPENFABRIEKEN, OF EINDHOVEN, NETHERLANDS.

VACUUM PUMP.

Application filed November 11, 1924, Serial No. 749,199, and in the Netherlands May 5, 1924.

This invention relates to metal vapour jet pumps and more particularly to pumps in which mercury vapour is used. It may, however, also be applied to pumps operating, for example, with the vapour of metals that have at ordinary temperatures a lower vapour pressure than mercury, such as lead, tin, bismuth, cadmium, zinc and the like.

It is known to construct mercury vapour jet pumps that have several stages. As a rule these pumps are provided with one or more annular jet tubes and with a centrally arranged jet tube of circular section whilst the mercury vapour between two successive stages is condensed by cooling. Such jet pumps have the disadvantage that the vapour stream through the annular jet tubes is difficult to regulate. As known the vapour speed in the successive jets in multi-stage mercury vapour jet pumps has to be regulated exactly relatively to each other, in order to ensure a good operation of the pump. It is not difficult to choose form and section of the central jet tube so that they meet the requirements; this is, however, a difficulty in the annular jet tubes, as in them even slight differences in the distance between the two walls of the jet tube exercise great influence on the total surface of the annular aperture and consequently on the velocity of the vapour.

In order to obviate the said disadvantage the metal vapour stream through the annular jet tubes is regulated according to the invention by means of a partition in which several apertures are provided. This partition is preferably arranged before the outlet end of the annular jet tube corresponding to it. The invention offers the advantage in addition to the one already mentioned that the walls of the annular tubes can be fixed rigidly and in the correct position relatively to each other in a simple manner.

Very good results are obtained with the pump according to the invention, if it is made of metal.

The successive jet tubes may be branched in the known manner from a common vapour supply tube. In such a construction the partitions provided with apertures are preferably arranged near the points where the vapour supply tube branches to the annular jet tubes which ensures a plain construction.

The apertures may then, for example, be

provided in the wall of the common vapour supply tube. Also according to the invention at the end of the common vapour supply tube a separate inserting member may be arranged consisting of the jet tube 60 for the vapour jet of circular section having fixed to it the partition perforated with apertures corresponding to one or more annular jet tubes.

The accompanying drawing illustrates, by way of example, a jet pump operating this mercury vapour. The pump shown in the drawing is entirely made of metal, the invention may, however, also be applied to glass pumps.

The vessel 1 contains a quantity of mercury 15, which is heated in some suitable manner, for example, with the aid of a gas burner. The mercury vapour that is formed, flows through a metal tube 2, which is surrounded by a heat-insulating jacket 3. When the mercury vapour has reached the end of a downwardly bent portion 4 of the tube, it flows partially through a number of apertures 6, and partially through a conical hole 16 in a nozzle 5. The vapour that has passed through the apertures 6, flows then through an annular jet tube, which is formed by a cylindrical wall 17, supported by legs 20 and the outer wall of the nozzle 5. After leaving an annular outlet aperture 18 and an outlet aperture 19 of the nozzle 5, the mercury vapour condenses on the wall of a vessel 7 which is constricted at 8 and is cooled by means of a cooling liquid that flows through a cooling vessel 9, having supply and discharge conduits 10 and 11. On one side a high vacuum conduit 12, on the other side a pre-vacuum conduit 13, communicated with the vessel 7. The condensed mercury flows through a tube 14 back again to the vessel 1.

The working of the pump, caused by the two jets of mercury vapour, is based on known principles and will herein not be described in detail.

The good results obtained with the pump according to the invention, are owing to the fact that it is easier to provide a number of small apertures of determined section in a wall, than to regulate exactly an annular aperture of minute width. If the pump, does not entirely meet the requirements, the small apertures can easily be perfected so that the vapour jet through the annular jet

tube obtains the desired velocity or again the apertures may be of regulable size, for example, by arranging two parts adapted to move over each other and provided with apertures, this is, in particular, easy if the pump is made of metal.

The vapour jet pump according to the invention, may be used for different purposes, for example, for exhausting electric incandescent lamps, for which purpose it operates in series with a pre-vacuum pump. The pump according to the invention, may be constructed in such a manner, that it can operate with a comparatively bad pre-
15 vacuum of for example 20-60 millimetres, whilst it on the other side is able to reach a high vacuum of 0.01 micron. The pump can also operate in series with another high vacuum pump for example with a pump of
20 similar construction, in which consequently the pre-vacuum is very good.

What I claim is:

1. A metal vapour jet pump comprising in combination a central jet and at least one removable member forming one or more annular jet tubes with said jet, a partition, and apertures in said partition by means of which the stream of metal vapour through said annular tubes is regulated.
2. A metal vapour jet pump comprising in combination a central jet and at least one removable member forming one or more annular jet tubes with said jet, a partition and apertures in said partition, the latter being arranged before the outlet of the corresponding annular jet tube and being adapted to regulate the stream of metal vapour through said annular jet tubes.
3. A metal vapour jet pump comprising in combination a central jet and at least one

removable member forming with said jets one or more annular jet tubes, said members and said central jet being made of metal, a partition, and apertures in said partition, the latter being arranged before the outlet 45 of the corresponding annular jet and being adapted to regulate the stream of metal vapour through said annular jet tubes.

4. A metal vapour jet pump comprising in combination a central jet and at least one 50 metallic removable member forming with said jet one or more annular jet tubes branching from a common vapour supply tube, a partition, and apertures in said partition, the latter being arranged near the 55 points where the vapour supply tube branches to said annular jet tube and adapted to regulate the stream of metal vapour through said apertures.

5. A metal vapour jet pump comprising 60 in combination a vapour supply tube, a central jet and at least one removable member forming one or more annular jet tubes with said jet, said jet tubes branching from said supply tube, a partition, apertures in said 65 partition, the latter being adapted to regulate the vapour stream through said annular jet tubes and being arranged near the points where said vapour supply tube branches to said annular jet tubes, a separate inserting 70 member, the latter being arranged at the end of the vapour supply tube and consisting of the jet tube for the vapour jet of circular section, said member having fixed to it the partition perforated with apertures corresponding to one or more jet tubes. 75

In testimony whereof I affix my signature, at the city of Eindhoven, this 22nd day of October, 1924.

CORNELIS BOL.
